TOY FILM VIEWER

Meyer M. Brown, New York, N. Y.

Application September 22, 1948, Serial No. 50,522

10 Claims. (Cl. 40—71)

1

This invention relates to a toy film viewer, particularly to a film viewer for viewing a plurality of pictures in succession by means of a lens focused upon the pictures.

One of the objects of the invention is to provide a toy film viewer of the general type, above referred to, which is very simple and sturdy in design and can be inexpensively manufactured.

Another object of the invention is to provide a toy film viewer of the general type, above referred to, which consists of few parts, and can be easily assembled and disassembled for the purpose of inserting or replacing a film so that the viewer can be handled by the operator without difficulty and without the need of technical skill or experience.

Another object of the invention, allied with the preceding one, is to provide a toy film viewer which comprises as principal parts, a casing including the lens, a cover detachably secured to the casing, and support means for supporting a film being held between the casing and the cover.

Another object of the invention is to provide a novel toy film viewer of the general type, above referred to, shaped to simulate a radio set or a television set or another suitable item, the lens being inserted in the front wall of the casing.

Another object of the invention is to provide a novel toy film viewer of the general type, above referred to, comprising a casing providing storage space for one or more films.

Another object of the invention is to provide a novel toy film viewer of the general type, above referred to, in which successive pictures viewable through the lens are mounted on a circular disc rotatably disposed between the casing and the cover by means of a pivot pin, said cover including an opening or window for framing individual pictures as they are successively placed in alignment with the opening.

Other and further objects, features and advantages of the invention will be pointed out hereinafter and set forth in the appended claims forming part of the application.

In the accompanying drawing a now preferred embodiment of the invention is shown by way of illustration and not by way of limitation.

In the drawing:

Fig. 1 is a front view of a toy film viewer according to the invention.

Fig. 2 is a side view of Fig. 1.

Fig. 3 is a rear view of the view finder of Fig. 1.

Fig. 4 is a view of the casing showing the interior thereof.

Fig. 5 is an exploded view of the film viewer according to the invention, and

2

Fig. 6 is a plan view of a picture bearing film disc as may be used in connection with the viewer.

Referring now to the figures in detail, the toy film viewer according to the invention comprises a casing 1 and a cover 2. The casing may be made of plastic, metal or any other suitable material. Similarly, the cover may be made of plastic, metal or other material.

10 The casing may be shaped and designed to simulate a radio receiver set, particularly a television receiver set having a screen 3 and control knobs 4. However, it should be understood that it is well within the scope of the invention to provide any other desired shape for the casing of the viewer, for instance the casing may be shaped to simulate an item of merchandise. The film disc, which will be more fully explained hereinafter, may then bear pictures advertising the item simulated by the shape of the viewer. Any other shape, for instance the shape of a figure, may also be employed which shape may or may not bear a relation to the pictures to be viewed by means of the viewer.

20 25 The front wall of casing 2, preferably the screen portion 3 thereof, serves as support for a lens 5 which may comprise a simple magnifying lens or a more complicated lens means if so desired. The lens is secured to the front wall of the casing by any suitable means and positioned in alignment with a window 6 in cover 2. The outline of window 6 may be of any suitable shape, preferably it is shaped approximately corresponding to one of the pictures to be viewed. In this 30 35 exemplification of the invention, as shown, the window outline is composed of a semi-hexagon completed by a section of the periphery of a circle, as can best be seen on Fig. 3.

Cover 2 can be removably secured to casing 1 by any suitable means. According to a now preferred arrangement, two noses or projections 7 extend from the top wall of casing 1 and are arranged to engage corresponding hooks 8 of cover 2. These hooks are shown as extensions of the cover bent off at a substantially right angle.

40 45 As will be evident, noses 7 and hooks 8 form two hinges for the cover which is secured to the casing along its opposite edge by means of a somewhat springy clamp 9 arranged to snap over a nose 10 at the bottom wall of casing 1. It will be apparent that it is also possible and quite practical in some instances to provide noses 7 and 10 on the cover and the hooks and the clamp on casing 1. Furthermore, recesses engaged by the hooks may be provided instead of projections 55 55 7.

The pictures to be viewed by means of the film viewer are shown as being mounted on a substantially circular disc 11 made of translucent or transparent material suitable for use as a transparency, such as a film. In the embodiment shown, five pictures are spaced about the center of the disc, as can best be seen on Fig. 6. However, any greater or smaller number of pictures may be employed. Pictures may be either black and white or colored. The term "picture," as used herein, is intended to include also print or script. It will be evident that the shape of the film disc is not necessarily circular and that the pictures may be spaced and shaped in various manner. It is merely essential that the pictures are so disposed on a carrier that they can be successively placed in alignment with lens 5 and window 6.

For the purpose of mounting the disc, the same is provided with a center hole 12 by means of which the disc can be slipped on a pin 14 extending from a bracket 15 secured to a wall for instance the front wall of casing 1. The end of pin 14 is arranged to extend into a hole 16 of cover 2, thereby securing the disc between casing and cover when the cover is secured to the casing. The center of hole 16 may be positioned so as to constitute the center of rotation of the curved portion of the outline of window 6. As can be clearly seen on the figures, the position of pin 14 and the diameter of disc 11 are so selected that the disc protrudes slightly beyond cover 2 and the top wall of casing 1, thereby permitting rotation of the disc, preferably manually, about pin 14. Lens 5 is focused upon a film disc supported on the pin.

To facilitate a close fit of the cover to the open side of the casing without impeding rotation of the disc, a recess 17 is provided at the upper edge of the casing and the cover is also recessed at 2' from which recesses the film disc protrudes, thereby leaving sufficient space for a free rotation of the disc.

While the described rotatable support of the disc has been found highly practical and is preferred at the present time, it will be obvious to any person skilled in the art that various other means may be provided for rotatably supporting the disc. For instance, pin 14 may extend from the cover into a corresponding hole 16 in the casing. Furthermore, the pin may extend directly from a casing wall rather than from a bracket supported on a wall of the casing.

It will be obvious that any one of the pictures on disc 11 which is rotated into alignment with lens 5 and window 6 may be viewed through the lens, the picture being framed by the window. To prevent warping or bending of a disc placed on pin 14, thereby adversely affecting the presentation of a picture, bracket 15 may be provided with two slanted arms or wings 18 and 18'. The angle of these wings preferably corresponds approximately to the angle of the respective sides of window 6. The wings are disposed in axial alignment with the lens and the window. As will be apparent, wings 18 and 18' serve to support a film disc slipped on the pin and also assist in the framing of the pictures.

Bracket 15 is preferably so disposed within the casing that it confines storage spaces 19 and 20 in which additional film discs may be placed, thereby making it conveniently possible to vary the pictures viewable by means of the viewer.

The operation of a toy film viewer according to the invention is as follows:

A film disc 11 is placed on pin 14. Then cover 2 is secured to the casing, the film disc now being rotatable between casing and cover. When the operator now places one of his eyes close to lens 5 while holding window 6 toward the light, a clear magnified presentation of the picture placed in alignment with window 6 will be viewable, the outline of the picture being distinctly framed by the window. By placing a finger against the protruding portion 11' of the film disc, the operator can conveniently rotate successive pictures into alignment with the lens and the framing window. When it is desired to exchange the film disc, the cover is snapped off the casing and another disc is slipped on pin 14 after removing the first disc.

As will appear from the previous description, the film viewer herein described offers the possibility of showing a great variety of pictures. By reason of its smallness and simplicity it can be either used as a toy for a child or as an advertising device.

While the invention has been described in detail with respect to a certain now preferred example and embodiment of the invention it will be understood by those skilled in the art after understanding the invention, that various changes and modifications may be made without departing from the spirit and scope of the invention and it is intended, therefore, to cover all such changes and modifications in the appended claims.

What is claimed as new and desired to be secured by Letters Patent is:

1. A toy film viewer comprising in combination a substantially rectangular box shaped to simulate the cabinet of a television set, the rear wall of said cabinet being open, a lens mounted in an opening of the front wall of said cabinet substantially flush with said wall, a substantially rectangular cover member, clamping means on the cover member and receiving means on a wall of said cabinet engageable one with the other for removably attaching the cover member to the cabinet, the top wall of the cabinet being recessed to provide a slot between the cabinet and the attached cover member, said cover member including a window positioned in optical alignment with said lens, a substantially circular film disc having a center hole and a plurality of transparent pictures thereon spaced about said center hole, support means extending into the cabinet from the front wall thereof, and a pivot pin protruding from said support means for rotatably supporting the film disc in a position in which a marginal portion thereof protrudes from said slot and in which different pictures are placed in optical alignment with the lens and the window in response to a rotation of the disc, said support means forming an abutment for a film disc placed on the pivot pin, said lens being focused upon a film disc placed on the pivot pin.

2. A toy film viewer comprising in combination a generally rectangularly shaped box, the rear wall of said box being open, a lens mounted in an opening of the front wall of the box, a cover member for the open wall of the box, clamping means for removably attaching the cover member to the box, said box and said cover member being shaped to form a slot between the top wall of the box and the attached cover member, said cover member including a window positioned in optical alignment with said lens, a film disc having a center hole and pictures thereon spaced about said center hole, support means extending

into the box from the front wall thereof for rotatably supporting the film disc in a position in which a marginal portion thereof protrudes from said slot and in which different portions of the disc are placed in optical alignment with the lens and the window in response to a rotation of the disc, said support means forming an abutment for a film disc placed upon the support means, said lens being focused upon a film disc placed upon the support means.

3. A toy film viewer as defined in claim 2, wherein said support means are shaped and arranged to support said film disc at the center hole thereof and at points radially spaced from said center hole.

4. A toy film viewer as defined in claim 3, wherein dependent wings extend from the support means and are arranged to support a film disc placed upon the support means.

5. A toy film viewer as defined in claim 2, wherein said support means include a pin forming a pivot for the film disc.

6. A toy film viewer as defined in claim 5, wherein said cover member includes an aperture in alignment with said pin for securing the film disc between the support means and the cover member.

7. A toy film viewer as defined in claim 2, wherein the edge of the top wall of the box is recessed to define together with the attached cover member the said slot for the film disc.

8. A toy film viewer, as described in claim 2, wherein said support means are shaped and arranged to form a substantially triangular abutment for a film disc placed on the pivot pin, the said pin being positioned at the apex of said triangular abutment and the optical axis between the lens and the window passing through the triangular space defined by said support means.

9. A toy film viewer, as described in claim 2, wherein each of said pictures on said film disc

forms an irregular polygon, and wherein the outline of said cover member window corresponds substantially to said outline of a picture.

10. A toy film viewer comprising in combination a box, the rear wall of said box being open, a lens mounted in an opening of the front wall of the box, a cover member for the open wall of the box, said box and said cover member being shaped to form a slot between the top wall of the box and the attached cover member, said cover member including a window positioned in optical alignment with said lens, a film disc having a center hole and pictures thereon, support means extending into the box from the front wall thereof for rotatably supporting the film disc in a position in which a marginal portion thereof protrudes from said slot and in which different portions of the disc are placed in optical alignment with the lens and the window in response to a rotation of the disc, said support means forming an abutment for a film disc placed upon the support means, said lens being focused upon a film disc placed upon the support means.
